CHAIN CUTTER FOR SEWING MACHINES

Filed Jan. 10, 1929

UNITED STATES PATENT OFFICE

FRIEDRICH LUTZ, OF STUTTGART, GERMANY, ASSIGNOR TO UNION SPECIAL MASCHINENFABRIK, G. M. B. H., OF STUTTGART, GERMANY

CHAIN CUTTER FOR SEWING MACHINES

Application filed January 10, 1929, Serial No. 331,441, and in Germany October 10, 1928.

The invention relates to new and useful improvements in chain cutters for sewing machines and more particularly to a chain cutter which is operated automatically for cutting the enchain thread loops between 5 stitched articles.

An object of the invention is to provide a chain cutting mechanism wherein the severing devices are power operated for severing 10 the chain, and wherein means is provided controlled by the fabric being stitched independent of the presser foot for causing the power mechanism to be connected to the severing devices after the stitched article moves 15 from beneath the presser foot for severing the enchain thread loops.

In the drawings:

Fig. 1 is a view showing more or less diagrammatically the improved chain severing 20 mechanism as applied to a sewing machine.

Fig. 2 is a sectional view on the line 2—2 of Fig. 1 showing the trimming lever and the control lever in plan.

Fig. 3 is a side view of the control finger 25 which brings about a connection of the severing devices to the power actuating means.

In my copending application, Serial No. 316,434, filed November 1, 1928, I have disclosed a chain cutter for sewing machines 30 wherein the chain severing devices are automatically connected to a power actuating mechanism by means controlled by the raising and lowering of the presser foot so that when an article being stitched passes from 35 beneath the presser foot, the chain severing devices will be connected to said power actuating means and the chain severed. The present invention is directed to a chain severing device of a similar character wherein the control 40 for coupling the movable severing device to the power actuating member is independent of the presser foot and through direct connection with the article being stitched.

45 By this arrangement, one article after another may be passed beneath the presser foot for stitching without the presser foot passing off from the first article onto the cloth plate and then being raised by the next article in order to bring about an actuation of

the severing devices. All that is necessary is to space the articles sufficiently so that the control finger will drop between the articles and this couples the actuating mechanism to the severing device which cuts the enchain 55 thread loops.

Referring more in detail to the drawings, the invention is shown as applied to a sewing machine wherein the needle head is indicated in part at 1. The needle bar is omitted and the presser bars indicated at 2, 3. One presser foot is indicated at 4 and the cloth plate on which the fabric rests at 5. These parts are all of the usual construction and detailed description thereof is not necessary. 65

Mounted on the cloth plate so that its cutting face is substantially flush therewith is a stationary trimming blade 6. Cooperating with this stationary trimming blade is a movable blade 7. In Fig. 1 of the drawings the 70 view is taken from the rear of the machine, and it will be noted that these trimming devices are arranged so as to operate in a plane at right angles to the line of feed for cutting the enchain thread loops between 75 stitched articles. The movable trimming blade 7 is carried by an arm 8. This arm is rigidly connected to a shaft 9. Rigid with the arm 8 is another arm 10. These two arms move as one with the shaft 9. The shaft 9 80 is mounted on a yoke bracket 11 which is fixed to the overhanging arm 12 of the machine. Pivotally connected to the upper end of the arm 10 is a latch or clutch member 13. Said clutch member is pivoted at 14 to said arm. 85 A spring 15 secured to the arm 10 by means of suitable screws bears on the tapered rear end of the clutch member 13 and normally turns said clutch member on its pivotal support in a clockwise direction. A stop screw 90 16 carried by the clutch member engages a shoulder 17 on the arm 10 and limits the clockwise movement of the clutch member.

A spring 18 coiled about a sleeve on the shaft 9 is secured at one end to the yoke bracket 11 and at its other end to the arm 8 carrying the movable trimming blade. This spring normally tends to raise the trimming blade from its operative relation to the stationary trimming blade 6. 95 100

Mounted on the overhanging arm is an actuating lever 19. Said lever is pivoted at 20 to the overhanging arm. This lever is continuously oscillated by means of a link 21 which is in turn actuated by a suitable connection with some moving part of the sewing machine. Mounted in the lower end of the lever 19 is a clutch member 22. Said clutch member is mounted in a socket or recess in the lower end of the lever and is held therein by screws 23, 23. The clutch member 22 is provided with an upturned end forming a shoulder 24. The clutch member 13 is provided with a knife edge 25. When the arm 10 is moved to a sufficient distance in a clockwise direction, the clutch member 13 will be so positioned relative to the clutch member 22 that the knife edge 25 will drop behind the shoulder 24 and the two clutch members will thus be joined together. When so connected the oscillations of the lever 19 will impart oscillations to the arm 10 which in turn oscillates the arm 8 and this will move the cutting blade 7 relative to the stationary blade 6 for cutting the enchain thread loops. This clutching of the movable cutting member to a power actuating device is shown and claimed in my copending application above referred to.

The present invention is directed particularly to the manner in which the connecting of the clutching members together and the disconnecting of said clutching members is accomplished. Mounted on the shaft 9 is a yoke member 26, which yoke member carries a control arm 27. Secured to this control arm 27 is a control finger 28. This control finger is provided with an inclined portion 29 and a foot portion 30. The foot portion 30 lies substantially beneath the arm 8 carrying the movable cutting blade 7. A spring 31 is coiled about a sleeve on the shaft 9 and one end of this spring is connected to the yoke bracket 11, while the other end is connected to the yoke member 26 carrying the control arm.

The control arm 27 extends upwardly from the yoke member as shown in Fig. 1 and thence laterally. Extending through the upwardly extending portion of the arm is an adjustable screw 32. The spring 31 is of greater tension than the spring 18. The spring 31 normally tends to move the control arm 27 in a clockwise direction which is contrary to the direction of movement of the arm 8 by the spring 18. When the arm 27 is permitted to turn in a clockwise direction the adjustable screw 32 engages the arm 10 and will turn said arm in a clockwise direction. This will lower the movable trimming blade into cooperative relation to the stationary trimming blade. The fabric being stitched is indicated in broken lines at F. The fabric is beneath the presser foot in Fig. 1 and the presser foot is raised. At this time the foot

30 of the control finger rests on top of the fabric and thus it is that the control arm 27 is raised.

When this control arm is raised then the screw 32 is moved out of contact with the arm 10 and the spring 18 raises the movable cutting blade 7 to its inoperative position. This movement of the arm 10 brings the shoulder 17 into contact with the stop screw 16 and will cause the knife edge 25 to be disconnected from the shoulder 24.

When the fabric F passes from beneath the presser foot even though another fabric section immediately follows so that the foot does not lower from the position shown in Fig. 1 the control finger will drop until it makes contact with the cloth plate. As it drops to this position through the action of the spring 31 then it is that the screw 32 engages the arm 10 and lowers the cutting blade 7 to co-operative relation with the stationary blade 6. This turning of the arm 10 in a clockwise direction will cause the clutch member 13 to move so as to come into engagement with the clutch member 22 and the movable cutting blade will be actuated through the connection with the power mechanism for severing the enchain thread loops. This actuation of the chain severing devices will continue until the control finger is raised. The control finger is raised by the fabric F passing underneath the same as shown in Fig. 3.

It will be apparent from the above description that I have provided a chain severing device for cutting the enchain thread loops between stitched articles which is power actuated and which is automatically controlled so that regardless of the position of the presser foot the movable chain severing device will be connected to the power actuating mechanism and operated to sever the enchain thread loops between stitched articles which are comparatively close together. Only sufficient space is necessary between the articles to allow the control finger to drop into contact with the cloth plate for a sufficient length of time to bring about a lowering of the movable cutting blade and a connection of the means which supports it to the actuating devices therefor.

It will be obvious that minor changes in the details of construction and the arrangement of the parts may be made without departing from the spirit of the invention as set forth in the appended claims.

Having fully described my invention, what I claim as new and desire to secure by Letters Patent, is:

1. In a sewing machine, a presser foot, a feeding mechanism, a stitch forming mechanism including a needle, and chain cutting devices located in rear of the needle and including a cutting blade, an oscillating member supporting said cutting blade, actuating

means for said cutting blade, a member mounted for oscillation about the same axis as the cutting blade and adapted to contact with the material passing under the presser foot, and means controlled by said member for connecting and disconnecting the cutting blade with its actuating mechanism.

2. In a sewing machine a presser foot, a cloth plate, a stationary cutting blade carried by the cloth plate, a rock lever, a movable cutting blade carried by said rock lever, a spring normally turning said rock lever to raise the movable cutting blade to inoperative position, a power actuating device, a clutch mechanism automatically connecting said actuating device to said rock lever when said movable blade is moved into operative relation to the stationary blade, a control arm having a control finger adapted to be raised by the article being stitched, a spring for normally moving said control finger into engagement with the article being stitched, an adjustable stop member on said control arm adapted to engage the rock lever, said spring operating the control arm being of greater tension than the spring operating the rock lever whereby when said article passes from beneath said control finger said control arm will move the rock lever bringing said movable cutting blade into cooperative relation with the stationary cutting blade.

In testimony whereof, I affix my signature.
FRIEDRICH LUTZ.
